ELECTRIC DISCHARGE TUBE COMPRISING
A DIRECTIONAL ELECTRON BEAM

Johannes de Gier, Eindhoven, Netherlands, assignor to Hartford National Bank and Trust Company, Hartford, Conn., as trustee

Application July 29, 1948, Serial No. 41,364
In the Netherlands September 12, 1941

3 Claims. (Cl. 250—162)

1

In electric discharge tubes comprising a directional electron beam and intended to reproduce television images, the electron beam produces a luminous spot on the screen. The latter may be either a luminescent screen or a thin metallic plate which is locally heated. The light intensity of the luminous spot increases, more particularly when use is made of a metal screen, as the accelerating voltage for the electrons is chosen to be higher.

It causes difficulties to raise the accelerating voltage with unvaried diameter of the tube. True the difficulties may be materially reduced by increasing the diameter of that portion of the tube in which the field electrodes are housed, but it is undesirable to increase the diameter of the tube in view of the increase in the diameter of the coils used for the electro-magnetic concentration and directioning of the beam and surrounding the tube. This would result in an increase of the energy necessary to generate the required field intensity and hence in supply devices of larger size.

The present invention relates to a device, the object of which is to raise the accelerating voltage to a considerable extent with unvaried diameter of a tube.

One of the factors preventing an increase of the accelerating voltage with the conventional arrangement of the electrode system on the stem secured by sealing to the glass neck of the tube is that the insulated wall portion over which the potential distribution occurs, extends from the anode to beyond the cathode so that at the area of the electron-emissive surface of the cathode the wall exhibits a potential which is materially higher than that of the cathode. This is favourable for the production of irregular voltage divisions over the wall, which may bring about sliding-spark discharges and punctures of the wall. The irregular voltage distribution and the sliding spark discharges are brought about by the modification of the uniform voltage distribution over the insulated wall by electrons which are freed from the surface area of the electrodes as a result of cold emission and which strike the wall of the tube.

According to the invention, the cathode is secured to a cylindrical insulator which fits in the glass neck of the tube, that surface of the insulator which is adjacent the wall being covered with an adhesive conductive layer which is either connected to the cathode or provided with a lead-out conductor. In the latter case the conductor is adapted to be connected to an earthed point of the supply unit if, as is frequently the case, the cathode is connected therewith by way of a resistance included in the supply unit.

It appears that sliding-spark discharges may have a particularly disadvantageous consequence

2

if they produce a high field-intensity in the vicinity of the cathode. The resulting forced discharge of electrons may cause an increase of the electron-emitting capacity of an oxide cathode such that the tube is thus rendered practically unserviceable.

In previous cases attempts have been made to avoid irregular charges of the wall in high-tension discharge tubes by surrounding the discharge path by a metal screen. A known construction in which this screen is formed as a part of the wall does not enter into consideration in the present instance. In a further known construction the screen is provided between the wall and the electrodes and is connected to the anode. This construction has the disadvantage that the diameter of the tube is required to be considerably larger than that of the electrodes. Since the charge of the screen is carried off, there is, moreover, some electron loss which has to be provided by the cathode of the tube, thus resulting in a higher load thereon.

Wall charges may be the result of cold emission at the edges of the electrodes. In order to avoid this phenomenon, attempts are made to work the surface of the electrode so accurately that it exhibits no irregularities, use being made in most cases of a metal having a high work function.

In a patent application previously filed it is assumed that in electron-ray tubes comprising a directional electron beam, which are surrounded by one or more magnet coils for controlling the path of the electron rays and of which the diameter is thus required to be as small as possible, electron-emission phenomena on electrodes, where such is not desired, may be avoided with great security by the arrangement of a metal screen, insulated from the electrodes, between the wall and that field electrode which is most adjacent the cathode, which screen extends from the tube wall in the space intermediate the field electrodes and terminates therein and intersects the electron paths, which otherwise would connect the field electrodes with the wall. Electrons which come available upon such electron-emission phenomena and which follow paths ending on the wall of the tube may release secondary electrons at the surface of the wall and thus bring about potential differences sufficiently high to initiate an electric spark discharge. If the lines of force along which the electrons travel terminate on a screen arranged in an insulated manner, this screen will be charged in a negative sense, so that further supply of electrons cannot take place. The screen may itself exhibit a shape which is as advantageous as possible for counteracting cold emission, since it does not fulfil a function in the electrode system for generating the electron beam.

60 This solution has been found to be not wholly

efficacious and more particularly it is not suitable to avoid harmful consequences of a spark discharge. The formation of such a spark not only discharges the insulated screen but also causes a strong charge thereof in the opposite sense and hence strong electric fields between the screen and the cathode with the harmful consequence already previously referred to.

According to a further feature of the invention, in an electron-ray tube in which the electrode system is housed in the glass neck of the tube, the tube wall and that field electrode which is most adjacent the cathode are separated by a metal screen which extends from the wall in the space between the field electrodes and terminates therein and is connected in an electrically conductive manner to the conductive coating provided on the cathode insulator. In this case the electric charge supplied as a result of spark discharge is carried off by the conductor connected to the conductive layer without any harmful effect being possible.

The invention will now be explained more fully by reference to the accompanying drawing, showing one example of the part of a cathode-ray tube containing the electrode system, to which the invention is applied.

The glass wall 1 surrounds the electron-emitting cathode 2 and the accelerating anode 3. The cathode 2 is secured to a cylindrical insulator 4 which fits in the glass neck of the tube and which may consist of ceramic material. The anode 3 is clamped in position in the tube by means of resilient members 5. A voltage difference of from 20,000 to 30,000 volts is applied between the cathode and the anode.

The insulating ring 4 also serves for the arrangement of the control electrode 6, to which a voltage is supplied which is adapted to vary between cathode potential and a negative value of a few hundred volts.

The surface of the ring 4 which is adjacent the wall of the tube is covered with an adhesive conductive layer 7 to which a supply conductor 8 is connected. This negative conductor may be connected to an earthed point of the source of high-voltage supply. Thus, in a determined circuit in which the control voltage is supplied by way of a resistance connected in series with the cathode, so that the negative voltage is produced as a voltage loss in this resistance and is obtained by the supply current of the device traversing the resistance, the conductive layer exhibits the same potential as the control electrode. In other cases, in which a separate source of supply is used to provide the control voltage, the conductive layer may be connected direct to the cathode as shown in the drawing.

The anode voltage applied to the tube during operation is set up between the conductive layer 7 and a conductive coating 10 which is provided on the wall of the tube and engaged by clamping springs 5 for supporting the anode 3. A distribution of voltage along the wall of the tube which is as uniform as possible facilitates satisfactory operation of the tube and decreases the risk of disturbances. If, however, the wall of the tube is struck by electrons of sufficient velocity to release secondary electrons, potential differences may arise and lead to an increase of the voltage gradient along the surface of the wall. A resultant voltage discharge will find a way from the conductive coating 10 to the other pole of the high-tension unit. The arrangement of a metal

screen 9, which extends from the wall in the space intermediate the field electrodes and terminates therein and is connected in an electrically conductive manner, to the conductive layer provided on the cathode insulator prevents the discharge from reaching the cathode. Although the risk of irregular charge of the wall is considerably reduced by the provision of the conductive layer on the surface of the cathode insulator adjacent the wall and the connection thereof with an earthed point of the high-tension source, the presence of the screen substantially avoids any detrimental consequences of a discharge, since the electric charge is in this case carried off by the shortest route without being capable of provoking undue field intensities in the vicinity of the cathode.

What I claim is:

1. An electric discharge device comprising an envelope having a tubular wall portion, a cathode source for generating a directional electron beam, first and second field electrodes within said envelope, a cylindrical insulating member interposed between said cathode source and said tubular envelope portion and fixedly securing said cathode source in spaced relation to said field electrodes, an adhesive electrically conducting layer interposed between said cylindrical member and said tubular envelope portion, and means to couple said conducting layer to said cathode.

2. An electric discharge device comprising an envelope having a tubular wall portion, a cathode source for generating a directional electron beam, first and second field electrodes within said envelope, a cylindrical insulating member interposed between said cathode source and said tubular envelope portion and fixedly securing said cathode source in spaced relation to said field electrodes, an adhesive electrically conducting layer interposed between said cylindrical member and said tubular envelope portion and directly connected to said cathode source.

3. An electric discharge device comprising an envelope having a tubular wall portion, a cathode source for generating a directional electron beam, first and second field electrodes within said envelope, a cylindrical insulating member interposed between said cathode source and said tubular envelope portion and fixedly securing said cathode source in spaced relation to said field electrodes, an adhesive electrically conducting layer interposed between said cylindrical member and said tubular envelope portion, means to couple said conducting layer to said cathode, and a metal screening member extending from the said wall portion and interposed between the said field electrodes, said screening member being electrically connected to said conducting layer.
